UNITED STATES PATENT OFFICE.

ADOLPH CULLANDER AND ENOCH HAGA, OF BELZONI, MISSISSIPPI.

COTTON TRAMPER.

Application filed April 18, 1924. Serial No. 707,452.

To all whom it may concern:

Be it known that we, ADOLPH CULLANDER and ENOCH HAGA, citizens of the United States, residing at Belzoni, in the county of Humphreys and State of Mississippi, have invented certain new and useful Improvements in Cotton Trampers; and we do hereby declare the following to be a full, clear, and exact description of the invention, such 10 as will enable others skilled in the art to which it appertains to make and use the same.

This invention relates to an improvement in cotton trampers and more particularly 15 to the control means for the operating mechanism in such machines.

The object of the present invention is to provide an improved and simplified control device by means of which power applied through a belt may be controlled by 20 the shifting of the belt and the corresponding application or release of a brake element through a mechanism of improved and simplified structure lending itself to 25 positive and efficient operation and simple attachment.

Other objects will more particularly appear in the course of the following detailed description.

30 The invention consists in the novel construction, arrangement and combination of parts as hereinafter more particularly described and claimed.

One sheet of drawings accompanies this 35 specification as part thereof, in which like reference characters indicate similar parts throughout.

Fig. 1 is an elevation illustrating the present device applied to a cotton trumper, 40 a portion only of the latter device being shown.

Fig. 2 is a plan view of the improved device removed from the machine.

Referring to the drawings 2 indicates a 45 drive shaft of the cotton trumper upon which are mounted a loose pulley 3' and a fixed pulley 3 over which a belt is adapted to pass as in common practice to apply power as desired to shaft 2.

50 Arranged transversely of the pulleys 3' and 3 and adjacent their periphery is a slidable rod 5 suitably mounted upon the framework 1 of the cotton trumper as by brackets 4 and 20. Upon the rod 5 are pivotally mounted spaced fingers 6—6 between which the belt is adapted to pass and by

means of which the belt may be shifted as desired on to the fixed or loose pulleys 3'—3 To one end of rod 5 is pivotally secured as at 7 a lever 8, which is again pivotally mounted as at 9 to a bracket 10 mounted upon the framework 1.

A cam member 11 is adjustably secured upon rod 5 as by bolts 12—12, this member 11 being provided with an inclined cam slot 65 13. A lever 14 is pivoted as by bolt 16 to a lug 15 forming part of bracket 4 and is pivotally connected as by bolt 18 to a brake shoe 19 positioned adjacent the periphery of fixed pulley 3. The other end of lever 14 is slidably secured as by bolt 17 which passes through the cam slot 13 to the cam member 11.

In operation the rocking of lever 8 will operate to shift the belt, for instance, from loose pulley 3' to fixed pulley 3, while at the same time cam member 11 will operate through slot 13 to release brake shoe 19. Conversely the shifting of the belt from fixed pulley 3 to pulley 3' will apply the 80 brake shoe 19 to fixed pulley 3, thus stopping shaft 2.

By adjusting the position of cam member 11 upon the rod 5 by means of bolts 12—12 the effective pressure exerted by shoe 19 85 may be varied as desired.

What we claim is:

1. In a cotton trumper having a drive shaft provided with a fixed and loose pulley, the combination of belt shifting means, 90 brake means, and means operatively associating the belt shifting means and the brake means, comprising a reciprocating member, a pivoted member, one end of the pivoted member associated with the reciprocating member by a part fixed with respect to one of said members, having a slot inclined with respect to the reciprocating member and a lug fixed with respect to the other of said members and operating in 100 said slot.

2. In a cotton trumper having a drive shaft with fixed and loose pulleys, a reciprocating rod, means for reciprocating the rod, belt engaging fingers mounted on the rod, a 105 cam member mounted on the rod, a lever carrying a brake shoe adapted to engage the fixed pulley, and means carried by the lever to engage the cam element.

3. In a cotton trumper having a drive 110 shaft with fixed and loose pulleys, a reciprocating rod, means for reciprocating the rod,

2
belt engaging fingers secured to the rod, a cam member longitudinally adjustable on the rod, a lever operatively associated with the cam member, and a brake shoe carried by said lever.

4. In a cotton trumper having a drive shaft with fixed and loose pulleys, a reciprocating rod, means for reciprocating the rod, belt engaging fingers secured on the rod, a member longitudinally adjustable with respect to the rod and having a slot

inclined with respect to the axis of the rod, a lever, a brake shoe pivotally mounted upon one end of said lever, and a bolt secured in the other end of the lever and passing through the inclined slot of the adjustable member. 15

In testimony whereof we affix our signatures.

ADOLPH CULLANDER.
ENOCH HAGA.
